DISPENSING UNIT HOUSING FOR FUEL OR THE LIKE

John Rogers Flannery, Jr., Fox Chapel, Pa., assignor to
Flannery and Associates, Inc., Pittsburgh, Pa., a cor-
poration of Pennsylvania

Filed Oct. 27, 1961, Ser. No. 67,278

Term of patent 14 years

(Cl. D52—2)

Fig. 3.

Fig. 4.

Fig. 1.

Fig. 2.

FIGURE 1 is a view in front elevation of a dispensing unit housing for fuel or the like embodying my new design, which is substantially the same in rear elevation;

FIGURE 2 is a view in side elevation of the dispensing unit housing shown in FIGURE 1 looking at the right-hand side thereof as it appears in FIGURE 1;

FIGURE 3 is a view in side elevation of the dispensing unit housing shown in FIGURE 1, looking at the left-hand side thereof as it appears in FIGURE 1; and

FIGURE 4 is a view in plan of the dispensing unit housing shown in FIGURE 1.

I claim:

The ornamental design for a dispensing unit housing for fuel or the like, substantially as shown and described.
